UNITED STATES PATENT OFFICE.

FRANZ A. FULLER, OF NEWARK, NEW JERSEY, ASSIGNOR TO J. E. MERGOTT COMPANY, OF NEWARK, NEW JERSEY, A CORPORATION OF NEW JERSEY.

BAG-FASTENER.

1,254,220.

Specification of Letters Patent. Patented Jan. 22, 1918.

Application filed November 21, 1914. Serial No. 873,261.

To all whom it may concern:

Be it known that I, FRANZ A. FULLER, a citizen of the United States, residing at Newark, in the county of Essex and State 5 of New Jersey, have invented certain new and useful Improvements in Bag-Fasteners, of which the following is a specification, reference being had therein to the accompanying drawings, which form a part thereof.

10 My invention relates to bag fasteners and more particularly to a type thereof applicable to bag frames having pivotally connected frame members and embodying therein a lift latch adapted to lock said frame members when closed.

15 In bag frames of the character above referred to, two hinged frame members formed of channeled metal stock are used, and the bag body is secured to the frame 20 by having the edges thereof inserted in the channel of said members. These edges may be held in the frame members in any desired manner or by any desired or well-known means.

25 The manner of connecting the bag body to the frame members, makes it highly desirable to keep the channel of said frame members free of obstructions, so as to avoid the necessity for cutting the edges of the 30 bag body or its support to clear such obstructions. This fitting not only causes additional labor in assembling the bag structure but additional tools and appliances are necessitated thereby.

35 In a bag fastener made in accordance with my invention, the controlling spring for the lift member or knob is so constructed, and so mounted in the frame member as to be substantially flat, parallel with and in close 40 juxtaposition to the top of the frame member, while it is especially adapted for use in connection with a bag frame member substantially rectangular in cross-section, it may, with slight modification be adapted to 45 a frame of any configuration providing that sufficient clearance is afforded adjacent the top of the frame to accommodate the spring and its tensioning means.

50 In the form of the invention shown, the tensioning means consists of a keeper adapted to operatively engage an angularly projected end of the spring, said keeper being firmly attached to the frame member by riveting, soldering, brazing or otherwise. 55 To bring the whole spring mechanism into

as small a compass as possible, the turned end of the spring is adapted to be seated between the top of the frame member and a depression in the keeper thus not only serving to develop, and maintain, the desired tension in the spring, but preventing axial displacement of the spring thus permitting the connection of the spring to the lift knob by means of a sliding fit between the spring and the socket in the spring lug. 60 That portion of the keeper bearing upon the top frame adjacent its point of connection therewith, is preferably stiffened, and one edge of the keeper adjacent the recess therein is cut away so as to avoid interference with the free action of the spring. 65 The construction and manner of attachment of the spring with relation to the frame is such as to bring substantially all portions thereof within the clearance necessary for 70 the free movement of the lug of the lift member or knob; and the application of the keeper to the frame member may not only be simply accomplished, but will result in 75 the tensioning of the spring so that the difficulties of mounting the spring with relation to the lift member or knob will be reduced to a minimum. Furthermore, the mounting of the lift member or knob and its controlling spring will require no modification of the frame member itself and thus 80 will not in any way interfere with the artistic lines of said member.

85 The invention consists primarily in a bag fastener embodying therein a channeled member having an opening therein adapted to receive the spring lug of the lift member or knob, a lift member or knob having a spring lug thereon adapted to be projected through said opening and within said channeled member, a spring having one straight section operatively connected with the lug of said lift member or knob and another straight section terminating in a projection extending angularly thereto, a keeper engaging the turned end of said last named spring section and a nose or catch adapted to be mounted upon a member movable with relation to said channeled member, and to be operatively engaged by said lift member or knob; and in such other novel features of construction and combination of parts as are hereinafter set forth and described and more particularly pointed out in the claims 95 hereto appended.

Referring to the drawings:

Figure 1 is a perspective view of a bag frame having my improved fastener mounted thereon, a portion of one of the frame members being broken away;

Fig. 2 is a view on a larger scale of a portion of the frame member carrying the lift member or knob;

Fig. 3 is a bottom plan view thereof;

10 Fig. 4 is a detailed view of the keeper; and
Fig. 5 is a detailed view of the preferred form of spring.

Like letters refer to like parts throughout the several views.

15 In the embodiment of my invention shown in the drawings, the channeled member supporting the lift member or knob is shown as consisting of one of a pair of hinged frame members *a*—*b*. These members each 20 consist of a main body having hinge members *a'* *a²* *b'* *b²* respectively. The said hinge members are pivotally connected at *c* and *c'*.

25 One of these frame members as *a* is provided substantially centrally thereof with an opening *d* adapted to permit the passage of the spring lug of a lift member or knob therethrough, which lug is exposed within the channel of the frame. The lift knob *e* 30 is of the usual and well-known construction being provided with a pendant rim *e'* adapted to project across the other frame member *b* and operatively engage the nose or catch *f* carried thereby. This lift member or knob 35 is provided with an integral lug *g* to which the controlling spring is adapted to be operatively connected in any desired manner. Preferably, however, this lug is provided with an angular socket adapted to receive a 40 spring, the end of which is so formed as to have a sliding fit therein.

In the practice of my invention, I employ 45 a controlling spring for the lift member or knob composed of two sections, one of which, as *h*, is operatively connected with the spring lug *g* and the other of which as *i* has its end *i'* turned at an angle thereto so that said section may be subjected to a twisting action to 50 develop a torsional stress thereupon, which stress is transmitted to the other section *h*. The section *h* is preferably connected to the spring socket *g* by having one end thereof as *h'* angularly formed so as to have a sliding fit within the socket in said lug. The 55 sections *h*—*i* are formed from a single strand of spring wire bent upon itself so as to bring said sections into a substantially parallel relation, the section *i* being of a length to bring the projection *i'* thereof beyond the end of the section *h* and at one side of the lug *g*.

To tension the said spring, the projection *i'* thereof is forced toward the top of the member *a* and held in this position by means of a keeper, one portion of which is adapted 65 to engage said end, and the other portion of

which is adapted to be permanently connected with or attached to the top of the said member *a*. This keeper preferably is in the form of a small bracket having one arm *j* thereof provided with reinforced stiffening 70 ribs *j'* and the other arm thereof *k* provided with a recess or seat *k'* adapted to receive the projection *i'*. Said bracket is adapted to engage the top of the said frame member so as to confine the projection *i'* and prevent its movement toward the lug *g*. To 75 facilitate the application of the keeper to the spring and to the frame member, I cut away a portion thereof as at *k²* and allow clearance for the spring section *i* adjacent 80 the projection *i'* thereof. The ribs *j'* terminate adjacent the transverse recess *k'*. The keeper is mounted in relation to the frame member *a*, preferably by means of a rivet *l* passing through the arm *j* and the 85 top of said frame, but if desired this keeper may be permanently secured in position in any other desired manner.

The arm *k* of said keeper, before it is assembled in the frame, is flat and projected at 90 an angle as indicated in dotted lines in Fig. 4, the recess *k'* being formed therein by means of a tool forcing said arm *k* to place after the arm *j* has been riveted to the frame. Downward pressure upon the arm *k* will 95 force said arm and the projection *l'*, thus exerting a torsional stress upon the spring section *i* and transmitting such stress together with a direct stress upon the section *h* with a resultant normal tendency to said 100 spring to tilt the lift member or knob toward the frame member *b* to a position where it will automatically engage the nose or catch *f*. The elongation of the section *i* will also permit that side sway thereof incidental to the actuation of the lift member or knob which is due to the eccentricity of the lug *g*.

The portion of the arm *k* adjacent the 110 cut away portion *k'* will, when the bracket is properly positioned, be forced against the top of the frame member *a*. Hence the section *i* will not interfere with the operation by which the final form is given to said bracket.

The lug *g*, the controlling spring coöperating therewith, and the bracket tensioning said spring, all lie in close juxtaposition to the top of the channel member carrying the same, and all of them project so slightly 120 into said channel as not to interfere in any way with the covering material for the frame or the edges of the bag body when they are inserted in the channel of, and secured to, said frame.

The form of said spring and the construction by which it is attached to the frame member *a*, are such as to preclude any possibility of its disarrangement. This condition avoids possibility of the accidental 125

opening of the bag through the breakage of the spring.

A bag fastener made in accordance with my invention is not only inexpensive to produce, but may be quickly and conveniently assembled.

It is not my intention to limit the invention to the precise details of construction shown in the drawings, it being apparent that such may be varied without departing from the spirit and scope of the invention.

Having described the invention, what I claim as new and desire to have protected by Letters Patent is:

15 1. A bag fastener embodying therein a channeled member having an opening therethrough adapted to receive the spring lug of a lift member or knob, a lift member or knob having a spring lug thereon adapted to be projected through said opening and within said channeled member, a looped spring having parallel sections, one of said sections being operatively connected with said lug and the other section terminating 20 in a projection extending angularly thereto, a keeper carried by said channeled member, engaging the said projection and tensioning said spring, and a nose or catch adapted to be mounted upon a member movable with 25 relation to said channeled member and to be operatively engaged by said lift member or knob.

2. A bag fastener embodying therein a channeled member having an opening therethrough adapted to receive the spring lug of a lift member or knob, a lift member or knob having a spring lug thereon adapted to be projected through said opening and within 30 said channeled member, a looped spring having parallel sections, one of said sections be-

ing operatively connected with said lug and the other section terminating in a projection extending angularly thereto, a keeper comprising an angular bracket one arm of which is permanently attached to said channeled member and the other arm of which is recessed to engage said projection and tension said spring, and a nose or catch adapted to be mounted upon a member movable with relation to said channeled member and to be operatively engaged by said lift member or knob. 45

3. A bag fastener embodying therein a channeled member having an opening therethrough adapted to receive the spring lug 55 of a lift member or knob, a lift member or knob having a lug thereon provided with an angular spring socket and adapted to be projected through said opening and within said channeled member, a looped spring 60 having parallel sections, the end of one of said sections having an angularly formed end adapted to have a sliding fit with said spring socket and the other section terminating in a projection extending angularly 65 thereto, a keeper carried by said channeled member engaging the said projection and tensioning said spring, and a nose or catch adapted to be mounted upon a member movable with relation to said channeled member and to be operatively engaged by said lift member or knob. 70

In witness whereof I hereunto affix my signature in the presence of two subscribing witnesses, this 14th day of November, 1914. 75

FRANZ A. FULLER.
